UNITED STATES PATENT OFFICE

2,204,670

WELT CEMENTING MACHINE

Andrew Eppler, Jr., Lynn, Mass., assignor to
 United Shoe Machinery Corporation, Borough
 of Flemington, N. J., a corporation of New
 Jersey

Application December 23, 1938, Serial No. 247,435

2 Claims. (Cl. 12—80)

This invention relates to cementing machines and is herein illustrated as arranged to apply cement to an inner surface of a ring welt, such as is shown, for example, in Letters Patent of the 5 United States No. 2,062,288, granted December 1, 1936, upon the application of P. C. Arnold.

In the manufacture of prewelt shoes, a ring welt, such as illustrated in the Arnold patent, is sometimes employed. This ring welt is of a length 10 which is sufficient for a single shoe and on one margin is split twice to provide three flaps, of which the one at the inside of the ring and the middle flap are sewed to opposite sides of the upper and the third or outer flap is attached to 15 the insole. It is desired to apply a coating of cement, such as latex, to one surface of the middle flap without at the same time coating the inner surface of the adjacent outer flap.

An object of the invention is to provide an 20 improved cementing machine having guiding means specially adapted for the coating operation.

As illustrated, and in accordance with a feature 25 of the invention, a device is provided for holding the outer flap away from the end surface of the coating applying roll and at the same time giving it a permanent set, which will prevent it from 30 springing back into contact with the surface of the middle flap to be coated until the upper has been inserted therebetween.

In the drawing:

Fig. 1 is an angular view of the machine embodying the invention;

Fig. 2 is a view in cross-section of the ring welt 35 attached to a short shoe upper and having its extension broken back preparatory to assembling with an insole for lasting; and

Fig. 3 is an enlarged vertical section taken 40 through the ring welt and the welt engaging members.

The invention is illustrated as applied to a machine of the type shown in Letters Patent of the United States No. 1,851,162, granted March 29, 1932, on the application of J. W. Cosgrove, to 45 which reference may be had for description of the parts of the machine which are not herein fully shown and described. As in the patented machine, a cylindrical applying roll 10 is supplied with cement, such as latex, by means of a transfer roll 12, to which a measured quantity is delivered by a pick-up roll 14 dipping in a trough 16. The latex is supplied to this trough 16 from an inverted bottle 18 and the quantity of the 50 coating material delivered to the transfer roll 12 is determined by a doctor roll 20, the position of

which may be adjusted by means of a thumb screw 22. Cooperating with the applying roll is a work-supporting roll 24 mounted in a pivoted arm 26, the position of which is determined in accordance with the thickness of the work by adjusting a hand wheel 28.

Laterally adjustable upon this arm is a gage 30 having a hooked portion 32 engaging the far edge of a split welt W and arranged to overlie a middle flap 34 and an inner flap of this ring welt W. 10 It is desired to apply latex to an inner surface of the split welt such as the upper surface of the middle flap 34 and at the same time to hold the outer flap 36 out of the way, so that no latex will 15 be applied to the inner surface of this outer flap 36 by reason of inadvertent contact with the end face of the applying roll 10. This is accomplished by means of a beveled plate 40, the inner face of which lies close to the end face of the applying roll 10 and the outer face of which meets the 20 inner face at a thin lower edge. This plate 40 is integral with an arm 42 having an out-turned lower end 44 adjustably secured to the gage 30 by screws 46 passing through inclined slots therein. The plate 40 performs the additional function of 25 holding the outer flap 36 at such a sharp angle with respect to the inner flap 34, that it is possible to apply cement all the way across the surface of the inner flap. At the same time, no coating is applied to the inner face of the outer flap 36 and 30 the latter is tilted so abruptly, with respect to the body of the work, that it is given a permanent set tending to maintain it in an outstanding position away from the cemented surface, until the latter has had a chance to dry.

In the operation of the machine the far edge of the welt is held against the hooked-shaped gage 32 by means of an outer hooked-shaped member 50 engaging the near edge of the welt. The member 50 is adjustably mounted on the gage 30 by means of clamp screws 52, which pass through slots substantially parallel to the slots receiving the clamp screws 46. This allows the outer hooked-shaped member 50 to be adjusted for different widths of welts and, when clamped in proper position, a ring welt may be inserted in the machine and allowed to move forward without further assistance from the operator until the whole of the surface of the middle flap 34 has been coated.

Having described my invention, what I claim as new and desire to secure by Letters Patent of the United States is:

1. In a machine for coating an inner surface of a strip, the edge of which has been split, form-

- ing a flap, an applying roll having a substantially cylindrical applying surface and an end face, a thin edged plate extending across the end face of the applying roll to hold the flap out of contact therewith, and a member engaging the outer edge of the strip thereby holding the flap against the thin plate.
5. In a machine for cementing an inner surface of a strip of welting, the edge of which has

been split to form a flap, an applying roll, a supporting roll coating therewith, hooked-shaped members for engaging opposite edges of the strip, and a plate extending across the end face of the applying roll, said plate being beveled to provide a thin lower edge and being mounted for adjustment toward and away from the applying roll.

ANDREW EPPLER, JR.
